ELEVATOR DOOR HANGER

Filed Sept. 25, 1928

FIG. 1.

FIG. 2.

INVENTOR:
THOMAS J. OSINGA

by *Milo B. Teocado*
ATTORNEYS.

UNITED STATES PATENT OFFICE.

THOMAS J. OSINGA, OF CHICAGO, ILLINOIS.

ELEVATOR-DOOR HANGER.

Application filed September 25, 1928. Serial No. 308,290.

My invention relates to means for suspending sliding doors, and more particularly to the means for balancing and lubricating the hangers which constitute the suspension 5 means for elevator doors, and my main object is to provide a novel hanger which is permanently lubricated.

A further object of the invention is to dispose the hanger in a novel oil well, which retains the lubricant in a confined state under 10 all conditions.

A still further object of the invention is to provide a novel sliding support for the hanger which is always properly aligned.

Another object of the invention is to incorporate in the novel hanger means to make allowance for slight deviations in the travel of the door, so that the sliding action of the door is not affected by such deviations.

A final, but nevertheless important object of the invention is to construct the novel hanger with few and simple parts of a rugged type, making the installation durable and the operation of the hanger efficient.

With the above objects in view and any others that may suggest themselves from the specification and claims to follow, a better understanding of the invention may be gained by reference to the accompanying drawing, in which—

Figure 1 is a fragmental elevation of a typical elevator door installation, showing the novel hanger applied; and

Fig. 2 is an enlarged section on the line 2—2 of Figure 1.

In the design of modern elevator installations, provision is made to suspend the door from hangers which have a sliding motion and incorporate ball or roller bearings to 40 reduce friction. While installations of this type are generally efficient, it is difficult to keep the sliding elements properly lubricated because of the exposed and complicated nature of the working parts. Dust settles in the latter and clogs what lubricant may be present, rendering the action of the door difficult and requiring frequent cleaning and adjustment. Also, conventional installations are subject to looseness and faulty alignment on 45 account of jars and deviations in the action of the door, causing much rattling and wear. I have endeavored to eliminate the above and other deficiencies found in the installations of the current type and to accomplish the objects outlined above to their fullest extent.

In carrying out the invention, specific ref-

erence to the drawing shows a typical beam 5 along which the door 6 is designed to operate. The novel door hanger is comprised mainly of a pair of channel supports 7 spaced laterally and having their base portions 7^a secured by a horizontal strap 8, making them rigid with relation to each other. As concerns the door 6, the same is supported from the bottom flange of each support 7 by a bolt 9, which is passed down with its shank through an aperture 10 in the flange, receiving a nut 11 immediately under the flange. The shank of the bolt extends downwardly to become screwed into the door 6 as indicated at 12, receiving a locking nut 13 above the door.

In conjunction with the hanger formed by the parts just described, in connection with the door, I use a novel receptacle 14. This receptacle is in the nature of a trough secured by bolts 15 or other means to the beam 5 and extends the length of the door's travel. The receptacle 14 receives on its bottom a longitudinal rail 16 having a head 17 of a substantially circular cross section. In connection with the head 17 of the rail 16, the top flange of each channel support 7 carries a depending arm 18 whose bottom is enlarged as indicated at 19 to be bored with a longitudinally-directed and tubular cavity 20, the latter opening downwardly. The cavity 20 is adapted to render the enlargement 19 of each arm 18 in sliding contact with the head 17 of the rail 16. This contact is eased by filling the trough 14 in the region of the sliding assembly with a quantity of oil or grease as indicated at 21. The mode of securing each arm 18 to the respective channel flange 7 is by a single medial bolt 22 directed from the channel into the arm, the latter, however, being flanged laterally as indicated at 23 for more stability. The bolt 22 is plainly shouldered in the region of the flange 7, as indicated at 22^a, and is not tightly driven up on the same, allowing a slight amount of lateral freedom on the part of the flange.

The installation described is shielded from dust by a cover 24 extended from the beam 5 over the parts. This cover has one or more depending angle bars 25 which form stops 105 for a depending continuation 26 of the cover, hinged to the latter at 27. This continuation may when closed be secured by bolts 28 to the bars 25; however, in the case of filling or emptying the trough by the use of a pressure or suction hose, the bolts 28 may be removed and the extension 26 swung away to permit

access to the trough. Considered as a unit the novel hanger may be designated as composed of the channel supports 7, their strap connections 8, the depending arms 18, and the rail 16 of the trough 14. It will be seen that the action of the hanger will be a purely sliding one with a maximum amount of lubrication to take the place of the more or less complicated ball or roller bearing installations of current types. With the lubricant in the elongated trough 14 at a level to well include the sliding assembly, the lubrication of the latter may be considered as perfect and permanent in a general sense. The stability of the rail 16, coupled with the spacing of the arms 18, gives the hanger a true alinement without the use of associate or other minor parts which are apt to get out of order or require frequent attention. At the same time, the ball and socket relation of the head 17 of the rail 16 and the enlargements 19 of the arms 18 provide a relation similar to that of a ball or universal joint, so that the door may undergo variations in its travel, such as from shock or rough handling, without affecting or impairing the alinement of its support, this alinement prevailing against all such shocks or variations. Further, warping tendencies on the part of portions of the door will be absorbed at the site of the bolts 22, these serving in the nature of king-bolts. Freedom at these points will relieve the arms 18 of tendencies to twist and bind along the rail 16 as the door moves. It is significant that the trough 14 is high, and serves to retain the lubricant against splashing or spilling over in case the door is roughly handled. Also, the simple assembly of the arms 18 with the single rail 16 makes for easier access in installation as against complications in this sense when many parts must be carefully fitted, as is the case with other installations. In conclusion, it will be evident that the benefits described are secured by an assembly of parts of extreme simplicity and rugged construction, making the novel hanger a mechanism which requires little or no attention and may operate efficiently for long periods.

While I have illustrated and described the invention in the preferred form, it will be evident that the same is capable of many minor changes and refinements, and it is my intention to include such changes and refinements as coming within the spirit and scope of the appended claims.

I claim:

1. A suspension for elevator sliding doors comprising a support, a trough attached to the latter and adapted to receive a lubricant, a track in the trough and parallel to the course of the door's travel, and means to support a door including a hanger suspending

the door, said hanger being supported for travel on the track.

2. A suspension for elevator sliding doors comprising a support, a trough attached to the latter and adapted to receive a partial filling of lubricant, a track along the bottom of the trough and parallel to the course of the door's travel, and means to support a door including a hanger suspending the door, a portion of said hanger being submerged in the lubricant to receive a support by the track for travel thereon.

3. A suspension for elevator doors comprising a fixed and elongated track having a crown of substantially circular cross-section, and means to support a door including a hanger suspending the door and formed with a socket conforming to and slidably engaging said crown.

4. A suspension for elevator doors comprising a fixed and elongated track of a relatively narrow dimension, said track having a top crown of substantially circular and enlarged cross-section, a means to support a door including hanger suspending the door and formed with a downward top bend, and a socket extended from the latter to rest upon and envelop the crown with freedom of angular and longitudinal sliding motions relative to the same.

5. A suspension for elevator sliding doors comprising a support, a trough attached to the latter and adapted to receive a lubricant, a track in the trough and parallel to the course of the door's travel, a hanger channel having a substantially horizontal course alongside the trough and with its flanges directed over and under the trough respectively, means to suspend the door from the lower flange, a track in the trough, an arm depending from the upper flange to receive a sliding support upon the track, and a bead-and-socket joint formed at the union of the arm and the track permitting transverse pivotal motion of the arm about the track.

6. A suspension for elevator sliding doors comprising a support, a trough attached to the latter and adapted to receive a lubricant, a track in the trough and parallel to the course of the door's travel, a hanger channel having a substantially horizontal course alongside the trough and with its flanges directed over and under the trough respectively, means to suspend the door from the lower flange, a track in the trough, an arm depending from the upper flange to receive a sliding support upon the track, and a king-pin connection between the upper flange and the arm to permit the flange to turn in a horizontal plane freely of the arm.

In testimony whereof I affix my signature.
THOMAS J. OSINGA.
